EUGENE MUNGER, OF BIRMINGHAM, ALABAMA, ASSIGNOR TO CONTINENTAL GIN COMPANY, OF BIRMINGHAM, ALABAMA, A CORPORATION OF DELAWARE.

VALVE MECHANISM FOR HYDRAULIC PRESSES.

1,292,355.

Specification of Letters Patent. Patented Jan. 21, 1919.

Application filed January 8, 1918. Serial No. 211,900.

To all whom it may concern:

Be it known that I, EUGENE MUNGER, a citizen of the United States of America, residing at Birmingham, in the county of Jefferson and State of Alabama, have invented 5 certain new and useful Improvements in Valve Mechanism for Hydraulic Presses, of which the following is a specification.

My invention relates to hydraulic presses 10 sure operated cotton trampers, baling presses and like mechanisms, and has for its object to design a mechanism for the joint manual and automatic control of the hydraulic valving mechanism which comprises a fluid distributing valve and a by-pass valve adapted 15 to short circuit the distributing valve under predetermined conditions to prevent excessive pressure conditions arising in the distribution valve or the press cylinder and its 20 piping system.

My invention is more particularly concerned with the mechanism for coöordinating the manual and automatic control of the by-pass valve at the completion of the follower's power or "down" stroke, my purpose 25 being to hold the by-pass valve open until the distributing valve shall have been reversed and then to cause the by-pass valve to automatically close so that pressure may 30 build up in the press cylinder to raise the follower. My preferred means for obtaining this desired control of the by-pass valve 35 contemplates the use of a floating lever connected to the by-pass valve and adapted to be operated to open the by-pass valve only 40 by the joint action of a manually controlled cam and a follower controlled actuator, the cam being connected so as to move with the distributing valve as it is manually reversed 45 and being designed then to release the floating lever and permit the by-pass valve, which is spring-pressed, to close automatically, whereupon the fluid pressure will become effective to raise the follower. The 50 by-pass valve at the end of the follower's return or up stroke is preferably controlled and opened by direct action from the follower, it being unnecessary in this case to close the by-pass valve before the follower 55 is started on its down stroke as it will, on reversal of the distribution valve, start down by gravity and permit the by-pass valve to close behind it.

My invention also comprises the novel details of construction and arrangements of 55 parts hereinafter pointed out in the appended claims and illustrated only in their preferred embodiment in the accompanying drawings which form a part of this specification, and in which:—

Figure 1 shows a hydraulic trumper mechanism with the follower at the top of its stroke and the cam and distribution valve in position before reversal to effect the down stroke of the follower.

Fig. 2 is a detail view of the by-pass valve in section with its control mechanism shown in elevation in the position assumed at the completion of the down stroke of the follower, and before the distributing valve and 65 cam have been shifted to release the by-pass valve and raise the follower.

Similar reference numerals refer to similar parts throughout the drawings.

As illustrated in the drawings, I have 75 shown my invention as embodied in the valve mechanism for a hydraulic cotton trumper of any standard construction, all details of which are omitted from the drawings excepting its follower 1 which is shown 80 attached to and operated by a piston rod 2 which is connected at its upper end to the piston 3 that is reciprocable in the press cylinder 4. This cylinder is mounted on the framing 5 and is connected at its upper end 85 by a pipe 6 to the valve chamber 7 of the casing 8 of the distributing valve 9. The lower end of the press cylinder is connected by a pipe 10 with the valve chamber 7, and fluid pressure is admitted to the chamber at 90 a point intermediate the ports for the pipes 6 and 10 by a supply pipe 11 having therein a check valve 12 and a by-pass valve 13 disposed in a return pipe 14 leading to the source of fluid pressure (not shown). The 95 fluid pressure exhausted from the press cylinder 4 by the valve 9 is returned to the source of fluid pressure by an exhaust pipe 15.

The distributing valve mechanism is preferably of the four-way balanced type and forms the subject matter in detail of an application for Letters Patent executed by me on December 31st, 1917, Ser. No. 210,951, filed Jan. 8, 1918, but other suitable forms 105 may be used. It is only necessary for the

purposes of this application to state that the valve 9 is a balanced piston valve having communication at both ends through an axial port with the exhaust 15 and intermediate reduced so as to alternately connect the supply pipe 11 with one of the distribution pipes 6 or 10 as the valve is operated, the pipe not thus brought into communication with the source of fluid pressure being open to the exhaust. The valve is operated by a stem 16 which passes out through a stuffing gland 17 in the casing 8 and is connected to a hand lever 18 on one side of a bearing pivot 19 therefor. On the other side of this pivot the lever 18 is connected by a link 20 with a crank arm 21 which operates a cam 22. This cam is preferably formed as a member pivoted on a bearing 24 and having a cam slot therein which is peculiarly shaped for the purpose of causing a guide pin 23, which works therein and is mounted on one end of the floating lever 25, to be raised and lowered a predetermined distance as the cam is thrown to one or the other of its extreme positions with the reversing movements of the distributing valve 9.

As shown in Fig. 1, the cam has been moved to raise the pin 23 to its position nearest the pivotal center of the cam whereas in Fig. 2 the pin is shown lowered to its remote position with relation to the pivotal center of the cam. The floating lever 25 at an intermediate point is pivotally connected by a pin 26 to the upper end of the stem 27 of the by-pass valve 13. A spring 28 acts on this by-pass valve to normally force it upwardly to its closed position in which the valve is balanced. The free end of the floating lever is disposed in the path of an actuator 29 carried at the upper end of an upright rod 30 mounted on and reciprocable with the follower 1. The position of the actuator is such that it will engage and depress the free end of the floating lever at the end of the follower's down or power stroke.

A lever 31 mounted on a fixed fulcrum 32 is also connected at one end to the by-pass valve stem 27 while the other end carries an adjustable tappet or stop 33 disposed in the path of a plate 34 on the follower disposed in position to engage the tappet and rock the lever at the end of the follower's up stroke, thereby automatically depressing and opening the by-pass valve.

In operation, it will be observed in Fig. 1 that the distributing valve and the cam controller for the floating lever move together but in reverse directions, they being shown in this view with the valve admitting pressure to the lower end of the press cylinder, as a result of which the follower has moved to the extreme of its up travel, leaving the near end of the floating lever 25 free while the cam end of the lever stands shifted to

raised position nearest the pivotal center of the cam. If now it is desired to cause a down or power stroke of the follower, the handle 18 is operated to reverse the position of the distributing valve 9 and at the same time the cam 22 is shifted so as to depress its end of the floating lever 25 to its lowered position, see Fig. 2, and this will result in causing the lever to rock on the valve stem and elevate its free end adjacent to the following. The spring 28 will hold the by-pass valve closed under these conditions and fluid pressure will be delivered through pipe 6 above the piston 3 to start the down travel of the follower. As the latter approaches the limit of its down stroke its actuator 29 will engage the floating lever, which then becomes fulcrumed on the cam 22, and depresses it sufficiently to force the by-pass valve to open position, thus automatically short circuiting the distributing valve and press cylinder by diverting the hydraulic pressure through pipe 14 back to the source of power. This short circuiting of the distributing system will prevent the building up of high pressures up to the capacity of the safety valve which would cause the disadvantages of operation described in my said pending application. At the completion of each down stroke of the follower the by-pass valve is opened by the joint action of the floating lever of the cam 22 at one end and the actuator 29 at its other end and the valve will remain in this open position until the lever 18 is reversed to divert pressure to the pipe 10 and to restore the cam to the position shown in Fig. 1, which will raise the outer end of the floating lever 25 and permit the by-pass valve to close responsive to the action of its spring 28, whereupon pressure will build up under the piston 3 and lift the follower. The cam and the distributing valve thus move together, the latter in conjunction with the actuator 29 giving the desired control of the by-pass valve at the completion of the power stroke of the press, whereas the lever 31 having the fixed fulcrum will automatically operate to by-pass the fluid at the completion of the up stroke. The reason it is unnecessary to develop a combined manual and automatic control of the by-pass at the top of the follower stroke is that the action of gravity on the follower will permit it to drop sufficiently on the reversal of the distributing valve to clear the lever 31 and permit the by-pass valve to close responsive to its spring, but where this gravity movement is not obtainable, the combined automatic and manual controller, through a floating lever, may be applied to operate the by-pass at both ends of the follower's stroke.

In the case of a trumper or like baling press where the follower is required to make a number of strokes and to move always to

the same point at the completion of its power stroke, I have found that as the cotton builds up under the follower it will cause the latter upon reversal of the distributing valve to rebound sufficiently to permit the by-pass valve to close without relying upon the cam or equivalent shifting fulcrum. In other words, under certain conditions a shifting fulcrum for the lever 25 is unnecessary and my invention therefore broadly contemplates that the operating connection between the distributing valve and the fulcrum for the lever 25 may be dispensed with, but such a connection is desirable as it will cause the by-pass valve to close in the desired manner under all operating conditions.

This invention is not intended to be restricted in scope to the specific embodiment shown, but contemplates such modifications as come within the spirit and scope of the claims.

Having thus described my invention, what I claim as new and desire to secure by Letters Patent, is:—

25 1. In a valve mechanism for hydraulic presses, a fluid distributing piping system, a multi-ported distributing valve and a by-pass valve included in said piping system, said by-pass valve being adapted when open to short circuit the distributing valve, manual means for reversing the distributing valve, an operating element for the by-pass valve, an actuator movable with the press follower, and an actuator movable with the distributing valve, said actuators being adapted to act jointly on said operating element to open the by-pass valve at the end of the follower's power stroke.

40 2. In a valve mechanism for hydraulic presses, a fluid distributing piping system, a multi-ported distributing valve and a by-pass valve included in said piping system, said by-pass valve being adapted when open to short circuit the distributing valve, manual means for reversing the distributing valve, an operating element for the by-pass valve, an actuator movable with the press follower, an actuator movable with the distributing valve, said actuators being adapted 45 to act jointly on said operating element to open the by-pass valve at the end of the follower's power stroke, said actuator movable with the distributing valve being adapted to release the operating element when the pressure is reversed to return the follower, and means to automatically close the by-pass valve when its operating element is released by said distributor valve actuator.

55 3. The combination with a hydraulic press having a follower, of a fluid distributing valve, a by-pass valve and pipe connections therefor to short circuit the distributing valve, manually controlled means to actuate the distributing valve, and mechanism responsive to the joint action of said manually

operated means and the press follower to open the by-pass valve at the completion of the power stroke of the press, and means to close the by-pass valve when released from said joint action, substantially as described. 70

4. The combination with a hydraulic press and its multi-ported control valve, of a self-closing by-pass valve adapted when open to short circuit the press, a cam movable with the multi-ported valve, an actuator movable by the press, and means responsive to the joint action of said cam and actuator to open the by-pass valve at the completion of the power stroke of the press. 75

5. The combination with a hydraulic press 80 and its multi-ported control valve, of a by-pass valve adapted when open to short circuit the press, a cam movable with the multi-ported valve, an actuator movable by the press, means responsive to the joint action 85 of said cam and actuator to open the by-pass valve at the completion of the power stroke of the press, said cam being movable upon the reversal of the multi-ported valve to release the by-pass valve, and automatic 90 means to close the by-pass valve, as and for the purposes described.

6. The combination with a hydraulic press and its distributing valve, of a self closing by-pass valve adapted when open to short 95 circuit the control valve, a floating lever connected to the by-pass valve, an actuator movable with the press follower to engage one end of said lever upon the completion of the power stroke of the press, and a cam movable with said distributing valve and adapted to engage the other end of the floating lever, the joint action of said actuator and cam serving to open the by-pass valve, 100 as and for the purposes described. 105

7. The combination with a hydraulic press and its multi-ported control valve, of a self closing by-pass valve adapted when open to short circuit the control valve, an operating stem for the by-pass valve, a floating lever fulcrumed intermediately on said stem, mechanism to reverse said control valve, a cam movable with said mechanism and adapted to control one end of said floating lever, and an actuator movable with the press follower and adapted to control the other end of the floating lever at the completion of the follower's power stroke, said cam and actuator serving jointly to hold the by-pass valve open until the cam is moved upon 110 the reversal of the control valve. 115

8. The combination with a hydraulic press, its platen and fluid distributing valve, of a self closing by-pass valve adapted when open to short circuit the distributing valve, 125 a stem for the by-pass valve, a lever having a fixed fulcrum connected at one end to said stem and at the other end disposed to be engaged by the follower at the completion of its up stroke and moved to open the by- 130

4
pass valve, and a second lever fulcrumed on said stem and having one end disposed to be engaged and moved by the follower at the end of its power stroke, a shifting fulcrum for the other end of said second lever, and means to shift said fulcrum with said distributing valve, as and for the purposes described.

9. The combination with a hydraulic press
10 having a follower and a fluid distributing valve, of a by-pass valve and pipe connections therefor to short circuit the distributing valve, leverage means adapted to be operated by the follower at the end of its
15 power stroke to open the by-pass valve, and means to close the by-pass valve when said

leverage means is released of the follower's pressure.

10. The combination with a hydraulic press having a follower and a fluid distributing valve, of a by-pass valve and pipe connections therefor to short circuit the distributing valve, leverage means adapted to be operated by the follower at each end of its travel to open the by-pass valve, and means to close the by-pass valve during intermediate positions of the follower.

In testimony whereof I affix my signature.

EUGENE MUNGER.
